UNITED STATES PATENT OFFICE.

JOHN G. ICKIS, OF ADENA, OHIO.

TROUGH FOR BANK WINDOWS.

Application filed April 9, 1926. Serial No. 100,829.

This invention relates to metallic deal troughs for bank windows, and more particularly to a trough of the character employed in association with the safety windows of cashier's and teller's cages.

The primary object of the invention is to provide, in association with a window having its lower sash or pane of bullet-proof glass disposed with its lower edge in or adjacent to the level of the deal plate or counter, a sunken metallic trough through which money, pass books, and the like may be passed beneath said pane, and which is so shaped that it affords to persons behind the window adequate protection against bullets fired into the trough passage.

In describing the invention in detail, reference is herein had to the accompanying drawings, in which—

20 Figure 1 is a cross section of the invention, illustrating its application; and—

Figure 2 is a top plan view of the trough mounted in position.

Referring to said drawings, 1 indicates one 25 of the pilasters provided at opposite sides of a window opening formed in the front wall or partition behind which the cashiers, tellers and other employees of a bank ordinarily perform their respective duties, and 2 and 3 designate the upper and lower bullet-proof glass panes of a window which constitutes a safety closure for said opening. The lower pane 3 is normally disposed with its lower edge in the plane of the top of 30 the usual deal table or counter 4, thereby to effectually obstruct the direct passage through the window opening of bullets fired from without the cage or enclosure.

Suitably countersunk in a channel provided therefor in the deal table 4 beneath the window opening is a transversely disposed metallic trough 5, of which the concave portion provides beneath the window pane 3 a passageway through which money, pass 45 books and papers may be readily passed or

transferred between the cashier and the bank's customers. The portion of the concave surface of the trough located outward of the window pane 3 presents a gradual incline, as shown, at 5^a, while the surface portion 5^b located inward of said pane is much more sharply inclined, possessing an arcuate curvature struck on a relative short radius and having a substantially vertical termination at the level of the table surface. So constructed, bullets fired inward through the passageway afforded by the trough and striking against said portion 5^b will thereby be deflected in an approximately vertical direction and thus be prevented from glancing at such an angle as would ordinarily endanger the persons of employees standing behind the cashier's deal plate 6.

Manifestly, the trough is readily accessible from both sides for the convenient removal 65 of money or articles passed therethrough.

What is claimed is—

A safety device for bank windows including teller's and customer's deal tables occupying a common plane and having a lower pane disposed with its lower edge normally occupying a position in the plane of the surface of said deal tables, a trough comprising a single depression substantially the width of the window forming a concave passageway beneath said pane and occupying a position in countersunk relation to said table surfaces, said trough having the inwardly disposed portion of its concave surface presenting a substantially arcuate curvature terminating substantially vertically of the table surface and having its outwardly disposed portion gradually inclined upward to said surface, the angle formed by the inner surface of the trough and deal table being of substantially greater degree than the angle of the outer surface of the trough and deal table.

In testimony whereof, I affix my signature.
JOHN G. ICKIS.
